GEORGE H. MELLEN, OF NEW YORK, N. Y.

Design No. 3,899, dated March 15, 1870.

DESIGN FOR CHILDREN'S CARRIAGES.

The Schedule referred to in these Letters Patent and making part of the same

---

I, GEORGE H. MELLEN, of the city, county, and State of New York, have invented and produced a new and original Design for a Combined Child's Carriage and Umbrella, of which the following is a specification.

The nature of my design is fully represented in the accompanying photograph, to which reference is made.

It consists of a carriage having carved, floriated, or otherwise ornamented sides and ends, surmounted by an open umbrella top, pendent from a curved holder springing from the rear end of the carriage, and rest-

ing on curved springs placed beneath the forward end of the carriage, there being, also, handles projecting upward from the hinder part of the frame, and the whole supported on wheels.

I claim as my invention—

The design for a combined child's carriage and umbrella top, as shown.

GEO. H. MELLEN.
